ATTORNEYS

UNITED STATES PATENT OFFICE.

MELBERN BENNIE BULLA, OF EL PASO, TEXAS.

SAFETY ATTACHMENT FOR AUTOMATIC TRAIN-STOPS.

1,387,233.

Specification of Letters Patent.

Patented Aug. 9, 1921.

Application filed July 2, 1919. Serial No. 308,107.

To all whom it may concern:

Be it known that I, MELBERN B. BULLA, a citizen of the United States, and a resident of El Paso, in the county of El Paso and 5 State of Texas, have invented a new and Improved Safety Attachment for Automatic Train-Stops, of which the following is a full, clear, and exact description.

This invention relates to automatic train stops and has particular reference to devices of the general character covered by Letters Patent of the United States No. 1,267,179, issued on the 21st day of May, 1918.

Among the objects of the present improvement is to correct certain defects or deficiencies in the previous structure and so make the device more practical and reliable.

In presentation of this invention for the convenience of all the readers of the present 20 as well as the previous specification, similar reference characters so far as expedient will be employed throughout the views of both cases.

Of said views—

25 Figure 1 is a diagrammatic side elevation of the improvement carried in a casing with a preferably glass front in the locomotive cab, but indicating also diagrammatically the contact devices for the track appliances; 30 and

Fig. 2 is a horizontal sectional detail on the line 2—2 of Fig. 1.

Referring now more particularly to the drawings I show a casing 10 through which 35 extends upwardly an air pipe 11 presumed to be in communication at its lower end with the train air line and open at its top to the atmosphere. Except as otherwise noted below the pipe 11 is normally held closed by 40 a trip valve 12 adapted to be operated for opening it by a lever 13 pivoted at 14 and having a rod 15 connected to a suitable power cylinder 16 in the upper portion of the casing.

45 17 is a branch pipe shown in this instance as leading laterally from the pipe 11 within the casing and hence being in open communication with the interior of said pipe 11 and normally charged with compressed air. This

50 charge of air is retained in the pipe 17 by means of a valve 18 held closed normally against the force of a spring 19 tending in connection with gravity to open the valve 18 to permit the compressed air to pass 55 through a pipe 20 to the cylinder 16 and also through a branch pipe 21 to actuate the

throttle lever, not shown, or any other device to be operated simultaneously with the setting of the brakes that will take place when the main valve 12 is open to permit 60 the air to escape through the main pipe 11.

The magnet 23 has an armature 24 connected to the valve 18 by means of a link 25 and so when the magnet is energized the valve is held closed in its normal position. 65 The battery 26 is carried at any convenient place and its energy is depended upon normally to energize the magnet 23. The course of such energy from the battery is through the wire 27, shoe 28, wire 29, pilot magnet 70 30, wire 45, armature 44, contact 46, wire 31, magnet 23, wire 32, contact piece 33, and wire 34 back to the battery.

A brush 35 along the track is adapted to be struck by the shoe 28 when a danger 75 signal is set and the train is attempted to be run past the danger point. The shoe is made the subject of a separate application of even date herewith, Serial No. 308,108. The brush is grounded at 36 and when the shoe 80 strikes the brush the energy from the battery 26 is momentarily dissipated to the ground causing the deenergization of both magnets 30 and 23. The circuit at this time will be from the battery through the wire 85 27, shoe 28, brush 35, ground 36 on one side and wire 34, contact piece 33, switch blade 37, contact piece 38, and wire 39 to the ground 40. The breaking of the circuit through the magnet 23 to cause the spring 19 90 95 to open the valve 18 admitting compressed air from the pipe 17 to the cylinder 16 causes the application of the brakes through the opening of the main valve 12. A counter 41 makes a record of this automatic opening of the train line through the link connection 42 with the lever 13. The magnets are again restored by swinging the lever 43 to the position shown in Fig. 1 which is done by the engineer manually. The armature 100 44 of magnet 30 acts as a switch blade between the wire 45 and the contact point 46. The wire 45 is normally idle being connected to the contact piece 47 adjacent to the contact piece 48 having connection through the 105 wire 49 with the bracket or contact 46. The spring 50 connected to the armature 44 tends to hold the armature away from the magnet and contact 46. To restore the armatures to normal position the switch blade 37 is 110 swung to the position shown bridging the gap between the contact pieces 47 and 48 at

which time the energy from the battery will pass through the magnet 30 as follows: wire 27, shoe 28 and wire 29 on one side, wire 34, contact piece 33, wire 32, magnet 23, wire 31, contact 46, wire 49, contact 48, switch 37, contact piece 47, and wire 45 on the other side. When the magnet is again energized as just stated the armature 44 will be lifted to normal position against the contact 46 10 where it will remain by virtue of the magnet even though the switch 37 be withdrawn from between the contact pieces 47 and 48. The lever 43 carrying the switch 37 is normally held bridging the contacts 33 and 38 15 by virtue of a spring 52.

If the engineer is instructed to pass a danger point he may do so by throwing the switch blade 37 away from the contacts 33 and 38 breaking the circuit to the ground 20 so that if the shoe strikes the brush the circuit through the magnets will not be disturbed. The upper end of the lever 43, however, is connected to a counter 51 so that a record is made of all of the times that the 25 lever 43 is actuated. If the engineer should undertake to defeat the purposes of the invention by holding, as by tying the lever 43 in its position spaced from the contacts 33 and 38, the air will be bled from the pipe 11 30 by means of a normally closed air cock 53, the valve of which is connected by means of a link 54 to the lever 43. The air cock 53 is provided with a small port 53', the capacity of which is not sufficient to stop a 35 train during the short time that elapses while the engineer is passing a switch under orders, but if he should undertake to tie the lever over against the force of the spring 52 the leakage through the port 53' would

be sufficient to cause the stopping of the 40 train. I provide also a vent 55 between the valve 12 and the top of the casing through which the train line may be bled as a result of the intended operation of the automatic devices even though some obstruction or 45 plug should be applied to the open end of the pipe 11 above the casing. The white and red lamps 56 and 57 are each arranged in multiple with the normally closed and danger circuits respectively so that the engineer will always know from an inspection 50 of the lamps the condition of the mechanism, and the lamps being in multiple in their circuits the circuits are not affected in case of a failure of either of the lamps, said circuits being conventional and *per se* forming no part of this invention are not illustrated. 55

I claim:

The combination with an air brake train line pipe, a normally closed valve serving 60 to maintain said pipe charged with compressed air and automatic means to open the valve when the train passes a danger point without authority, of an auxiliary valve having a small delivery port, electric 65 controlled means under the command of the engineer whereby he may pass a danger point under orders without causing the main valve to be opened or stopping the train within a reasonable time, and connections 70 between the auxiliary valve having the small port and the said electric controlled means whereby irrespective of the will of the engineer the train line pipe is bled of air and the train is caused to stop if the manually controlled devices are not restored within a reasonable time to normal position. 75

MELBERN BENNIE BULLA.
